(57) **CLAIM**

The ornamental design for a cone, as shown and described.

DESCRIPTION

FIG. 1 is a perspective top view of a cone showing our new design;

FIG. 2 is a top view thereof;

FIG. 3 is a side view thereof;

FIG. 4 is a perspective top view of the cone having beveled sides;

FIG. 5 is a top view thereof; and,

FIG. 6 is a side view thereof.

Only one representative side view of the design is shown as all side views are identical.
